UNITED STATES PATENT OFFICE.

HARRY S. STRONACH, OF OAK PARK, AND ROBERT C. ROWAN, OF WHEATON, ILLINOIS.

WIRE NAIL.

Application filed January 26, 1923. Serial No. 614,966.

To all whom it may concern:

Be it known that we, HARRY S. STRONACH and ROBERT C. ROWAN, citizens of the United States, residing, respectively, at Oak Park, in the county of Cook and State of Illinois, and at Wheaton, in the county of DuPage and State of Illinois, have jointly invented certain new and useful Improvements in Wire Nails, of which the following is a specification.

This invention relates to a new and improved nail and more specifically to a nail constructed to avoid splitting material into which it is driven.

15 Nails as at present commonly constructed are provided with points which are commonly pyramidal in form. Wire nails are cylindrical from the point to the head, being sometimes provided with serrations on the 20 body adjacent the head to aid in retaining them in place. When such nails are driven into wood or other fibrous material, the pyramidal point enters between the fibers and forces them apart an amount necessary to 25 permit passage of the cylindrical body of the nail.

When relatively thin wood or wood adapted to split easily is used and the nails are driven adjacent the ends or edges of the 30 wood strips, there is a marked tendency for the wood to be split by the entering action of the pyramidal point. It is necessary to displace sufficient of the wood fiber to provide an opening for the passage of the body of the 35 nail. This can be accomplished by dividing the fibers as is done by a pyramidal point, or it can be accomplished by cutting and crushing the fibers and to a certain extent carrying them down with the nail as it 40 enters, which method is accomplished by the forms comprising the present invention. Where the nail cuts, crushes or tears and carries with it the fiber, the fiber is cut and thus portions of fiber adjacent the nail opening 45 are not materially displaced. Lateral thrust is not sufficient to cause splitting.

It is an object of the present invention to provide a new and improved construction of the entering portion of nails whereby the 50 fiber may be cut and crushed rather than laterally displaced by the entrance of the nail in the material.

It is a further object to provide a construction of this character which is sym-

metrical whereby it operates equally efficiently regardless of the relative position of the nail.

It is an additional object to provide a nail construction adapted to carry the crushed and cut fibers down with the nail as it enters 60 the fibrous material.

It is also an object to provide a construction which may be readily manufactured at small cost and which is adapted for commercial production.

Other and further objects will appear as the description proceeds.

We have illustrated certain preferred embodiments of our invention in the accompanying drawings, in which:

Figure 1 is a side view of a nail constructed according to one form of our invention;

Figure 2 is a view of Figure 1 as seen from the right;

Figure 3 is a fragmentary section taken on line 3—3 of Figure 2;

Figure 4 is a view similar to Figure 3 showing a modified form of device;

Figure 5 is a view similar to Figure 3 showing a further modified form;

Figure 6 is a view similar to Figure 1 showing a modified form;

Figure 7 is a view of Figure 6 as seen from the right;

Figure 8 is a view similar to Figure 1 showing a further modification;

Figure 9 is a view of Figure 8 as seen from the right;

Figure 10 is a view similar to Figure 1 showing a still further modification;

Figure 11 is a view of Figure 10 as seen from the right; and

Figures 12 and 13 are views similar to Figure 2 showing further modified forms of the nail.

In the form of nail shown in Figures 1 to 3, the body of the nail 15 is substantially cylindrical in form and carries the flattened head 16. This design is similar to that of 100 the so-called wire nail as is at present in general use.

The entering portion of the nail is reduced by means of three chamfering cuts 17 so that its end 18 is approximately triangular in form. The edges formed by the intersection of the cuts 17 adjacent the end are stepped as indicated at 19. The axial faces

of these steps are substantially parallel to the axis of the nail. In the modified form shown in Figure 4, the faces 20 of the steps slope downwardly toward the nail point 5 while in the form shown in Figure 5, the faces 21 of the steps or serrations are reversely sloped.

The form of nail shown in Figures 6 and 7 is similar to that shown in Figure 1, with 10 the exception that the serrations 19 are omitted. In this form the three cuts 22 intersect substantially at the end of the nail and the end 23 is substantially triangular inscribed within the circle representing the 15 cross-section of the nail, as shown in Figure 7.

In the form of construction shown in Figures 8 and 9, the cuts 24 are made in a plane substantially parallel to the axis of 20 the nail with their lower portions 25 rounded off. In the form of construction shown in Figures 10 and 11, the end 26 of the nail is substantially square as shown in Figure 11, and is somewhat reduced in size from the 25 cross-section of the body of the nail. This square end 26 is secured by means of four cuts 27. In Figures 12 and 13, forms are shown which are generally similar to the form of Figures 6 and 7, the cuts forming 30 concave and convex surfaces 28 and 29, respectively, rather than the flat surfaces of the other figures. The entering face is thus a triangle with curved sides.

It is an essential feature of all forms of 35 the device that the entering face of the nail be of appreciable size and be upon a plane substantially transverse to the axis of the nail. This face enters the wood or other fibrous material by cutting the fibers upon 40 its edges and crushing the fibers around the cutting edge of the nail or the serrations instead of the usual spreading wedge effect. The serrations formed upon the types of 45 nails shown in Figures 1 to 5 aid materially in cutting and tearing the fibers sufficiently to avoid splitting thrust. This form of entering actions is distinctly different from the usual entering action of a pointed nail wherein the fibers are displaced laterally, 50 causing a tendency to split.

By means of the present construction, this 55 splitting tendency may be reduced to a minimum or may be eliminated. It is usually desirable that there be a certain amount of spread after the nail has begun to enter in order that there may be a gripping upon the nail to retain it in place. This gripping action is provided by means of the sloping cuts found upon the types of nails shown herein. 60 The amount of this action may be controlled by governing the size of the entering face; for example, it may be made relatively small as shown in Figure 2, or relatively large as shown in Figures 7 and 9, or of an intermediate size as shown in Figure 11. Obviously,

the serrations or steps shown in Figures 1 to 5 may be applied to the other forms of nail.

While we have shown various modified forms of our device, the construction is capable of further modifications and it is our intention to cover all such modifications as come within the scope of the appended claims.

We claim:

1. A nail comprising a head, a body of substantially uniform cross-section, and an entering end comprising a flat surface transverse of the axis of the nail, said flat surface covering a material portion 80 of the cross-sectional area of the nail body, and being less in area than said cross-section, said surface being joined to the lateral surface of the nail by sloping surfaces.

2. A nail comprising a head, a body of substantially uniform cross-section, and an entering end comprising a flat surface transverse of the axis of the nail, said flat surface covering a material portion of the cross-sectional area of the nail body, and being 90 symmetrical about the axis of the nail, said surface being joined to the lateral surface of the nail by sloping surfaces.

3. A nail comprising a head, a body of substantially uniform cross-section, and an entering end comprising a flat surface transverse of the axis of the nail, the surface being bounded by a plurality of straight lines, said lines being joined to the lateral surface of the body of the nail by means of 100 sloping surfaces.

4. A nail comprising a head, a body of substantially uniform cross-section, and an entering end comprising a flat surface transverse of the axis of the nail, the surface being bounded by a plurality of straight lines, said lines being joined to the lateral surface of the body of the nail by means of sloping surfaces, said sloping surfaces intersecting to form ridges sloping from the lateral surface to the entering surface.

5. A nail comprising a head, a body of substantially uniform cross-section, and an entering end comprising a flat surface transverse of the axis of the nail, the surface being bounded by a plurality of straight lines, said lines being joined to the body of the nail by means of sloping surfaces, said surfaces intersecting to form ridges sloping to the entering surface and serrations formed 115 in said ridges.

6. A nail comprising a head, a cylindrical body, and an entering end comprising a flat surface transverse of the axis of the nail, said surface being defined by lines each of a 125 length greater than the radius of the nail body.

7. A nail comprising a head, a cylindrical body, and an entering end comprising a flat surface transverse of the axis of the nail, 120

said surface being symmetrical about the axis of the nail and being defined by lines each of a length greater than the radius of the nail body.

5 8. A nail comprising a head, a cylindrical body, and an entering end comprising a flat surface transverse of the axis of the nail, said surface being defined by straight lines each of a length greater than the radius of 10 the nail body, said edges of the entering surface being joined to the surface of the nail body by sloping cutaway portions.

9. A nail comprising a head, a cylindrical body, and an entering end comprising a flat 15 surface transverse of the axis of the nail, said surface being defined by straight lines each of a length greater than the radius of the nail body, said edges of the surface being joined to the nail body by sloping cut- 20 away portions, said cutaway portions meeting adjacent the entering surface to form ridges, and serrations formed in the ridges.

10. A nail comprising a head, a cylindrical body, and an entering end comprising 25 a triangular flat surface transverse of the axis of the nail, the triangle being equilateral

eral and symmetrical about the axis of the cylindrical body, and being joined to the lateral surface of said body by sloping flat surfaces.

30

11. A nail comprising a head, a cylindrical body and an entering end comprising a triangular flat surface transverse of the axis of the nail, the triangle being equilateral and symmetrical about the axis of the 35 cylindrical body, and being joined to said body by sloping flat surfaces, the flat surfaces meeting to form ridges and the ridges being serrated.

12. A nail comprising a head, a body and 40 an entering end, said end joining the body by cutaway portions, the cutaway portions forming ridges at their points of junction with each other, and serrations formed in said ridges.

Signed at New York, New York, this 19th day of January, 1923.

Signed at Chicago, Illinois, this 24th day of January, 1923.
